UNITED STATES PATENT OFFICE.

GEORGE S. HENSEL, OF PHILADELPHIA, PENNSYLVANIA, ASSIGNOR TO
THE HENSEL, COLLADAY COMPANY, OF PENNSYLVANIA.

DESIGN FOR A SKIRT-PROTECTOR.

SPECIFICATION forming part of Design No. 32,264, dated February 20, 1900.

Application filed January 26, 1900. Serial No. 2,917. Term of patent 14 years.

To all whom it may concern:

Be it known that I, GEORGE S. HENSEL, a citizen of the United States, residing in the city and county of Philadelphia, State of Pennsylvania, have invented and produced a new and original Design for Skirt-Protectors, of which the following is a specification, reference being had to the accompanying drawings, forming part thereof.

The leading feature of my design for a skirt-protector is a border of serpentine form on the head of the protector.

Figure 1 represents a face view of a piece of skirt-protector embodying my design. Fig. 2 represents a section thereof on line $x x$.

In the drawings, A designates a piece of a

skirt-protector, the body of which consists of a head B and a brush C pendent therefrom. D designates a border of the body opposite to the brush, the same being of serpentine form and extending in the longitudinal direction of the piece.

Having described my invention, what I claim as new, and desire to secure by Letters Patent, is—

The design for a skirt-protector substantially as shown and described.

GEORGE S. HENSEL.
